UNITED STATES PATENT OFFICE.

JOHN J. FRANK, OF SCHENECTADY, NEW YORK, ASSIGNOR TO GENERAL ELECTRIC COMPANY, A CORPORATION OF NEW YORK.

TELEPHONE-TRANSFORMER.

No. 852,711.

Specification of Letters Patent.

Patented May 7, 1907.

Application filed August 14, 1906. Serial No. 330,561.

To all whom it may concern:

Be it known that I, JOHN J. FRANK, a citizen of the United States, residing at Schenectady, county of Schenectady, State of New York, have invented certain new and useful Improvements in Telephone-Transformers, of which the following is a specification.

In connection with modern high potential electric transmission lines, it is common practice to connect stations located at the terminals of, or along one line or system of lines by telephones. For convenience and to save expense the telephone line wires in such cases, are usually carried by the same supports which carry the high potential power transmission lines. Unless suitable provision is made for protecting the telephonic instruments, an electrical connection occurring accidentally between the transmission conductors and the telephone lines, is liable to result fatally to a person attempting to use any of the telephones at such time, or at least to produce serious damage to the apparatus.

The object of my present invention is the construction of a transformer adapted to be interposed between the telephone line proper and the conductors running to an individual telephone. Such a transformer must, of course, have its primary and secondary windings effectively insulated from each other in order to produce the desired results, and should be strong and compact in construction, with its windings effectively protected from the weather, since it must ordinarily be placed on a pole exposed to the weather.

The various features or novelty which characterize my invention are pointed out with particularity in the claims annexed to and forming a part of this specification.

For a better understanding of my invention and the manner in which I have attained the objects hereinbefore referred to, reference may be had to the accompanying drawings in which

Figure 1 is a perspective view of a transformer constructed in accordance with my invention; Fig. 2 is a plan view illustrating the core structure employed; Fig. 3 is a section of the transformer, shown in Fig. 1, and Fig. 4 is a section of the core on the line 4-4 of Fig. 2.

In the drawings, 1 represents a cup-shaped, shell-like member which may be formed of

cast iron or the like, and which has an axially disposed opening at its lower end in which is located a cylindrical bushing 2 of insulating material such as glass, porcelain or the like. The member 1 is provided with lugs 3 at one side. Supporting bolts may enter holes 4 formed in the lugs 3. At its upper end the member 1 is provided with a radially extending flange-portion 5. The lower edge of the core 6, which is cylindrical in outline, is supported on the flange 5, from which it is separated by suitable insulating washers 7. A second cup-shaped member 8 having a flange portion 9 similar to the flange portion 5 is supported from the upper side of the core by washers 10 which may be similar to the washers 7. The members 1 and 8, core 6, and washers 7 and 10, are firmly secured together by transverse bolts 11.

The core is composed of laminae 12 of the form shown in full lines in Fig. 2. Each lamina 12 being approximately E shaped. The windings of the transformer comprise a secondary coil 13 which surrounds the middle tongues of the punchings, and a primary coil 14 which surrounds the coil 13. The terminals 15 of the coil 14 which are connected to the line circuit pass out through the bore in the insulating bushing 2. The terminals 16 of the coil 13 pass laterally out of the member 1 through an elbow pipe 85 section 17 which may be adjustably secured to the member 1. The coils 13 and 14 are insulated from each other by cylindrical line member 18 of suitable insulating material, and the windings are surrounded and separated from the core by insulation 19.

The transformer core is assembled after the windings are formed. As shown by Figs. 1, 2 and 4, the adjacent punchings 12 are reversed with respect to each other so that the sections of the core by the line 4-4 have in them a thickness of iron half that of the portion of the core surrounded by the windings. The narrow openings through these sections of the core may be closed, to protect the windings against the weather, by dipping the transformer after assembly in insulating paint.

The arrangement described possesses excellent electrical and mechanical properties. The coils 13 and 14 are effectively insulated from each other. The core, due to the large overlap of the E-shaped members that com-

pose it, has a low magnetic reluctance and consequently requires only a small magnetizing current, so that only a small current is needed for ringing; while by forming the laminations of high resistance steel, losses are relatively small with the high frequency talking currents. The construction is very compact and the core and windings are well protected from mechanical injury and from the weather. If desired the frame 1 may be connected to earth by a conductor at 20.

What I claim as new and desire to secure by Letters Patent of the United States, is:—

1. In a transformer, two cup-shaped members, a magnetic core clamped between said members and forming therewith an inclosing casing, primary and secondary windings on said core within the casing, the lower of said members being extended downwardly below said windings and provided with an opening at its bottom, and an insulating bushing extending through said opening and providing a passage for the primary leads of the transformer.
2. In a transformer, two cup-shaped members, a magnetic core clamped between said members and forming therewith an inclosing casing, primary and secondary windings on

said core within the casing, the lower of said members being extended downwardly below 30 said windings and provided with a large opening at its bottom and a smaller downwardly projecting opening on one side, and an insulating bushing extending through the large opening and providing a passage for the 35 primary leads of the transformer, the secondary leads being carried out through the smaller side opening.

3. In a transformer, two cup-shaped members, a magnetic core clamped between said 40 members and forming therewith an inclosing casing, primary and secondary windings on said core within the casing, the lower of said members being extended downwardly below said windings and provided with an opening 45 at its bottom, an insulating bushing extending through said opening and providing a passage for the primary leads of the transformer, and supporting lugs on said lower member.

In witness whereof, I have hereunto set my hand this 11th day of August, 1906.

JOHN J. FRANK.
